PERSPECTIVE DRAWING MACHINE

Orrin F. Randolph, West Palm Beach, Fla.

Application June 8, 1948, Serial No. 31,760

9 Claims. (Cl. 33—1)

1

This invention relates to a machine or apparatus for facilitating perspective drawing.

One object of the invention is to provide an apparatus of the indicated character which employs relatively distant vanishing points and yet may be operated on a comparatively small drawing board.

Another object of the invention is to provide a means for producing views of an object in one, two, or three-point perspective, and to draw these views from either an actual object or from two or more related orthographic views of the object.

A further object of the invention is to eliminate the necessity for auxiliary construction lines on the perspective drawings.

It is likewise an object to provide an apparatus of the indicated character which may be operated quickly and accurately by a person relatively unskilled in the art of perspective drawing, the operation resulting in a minimum of mental fatigue for the operator.

It is also an object to provide an apparatus of the indicated character which is adapted to be mounted on a drawing board over the drawing paper so as to permit the use of any size drawing sheet.

Still another object is to provide an apparatus which is simple, efficient, and comparatively inexpensive and which may be divided into two separate units, either of which may be operated alone, if desired, but both of which cooperate together when combined.

It is even an object of the invention to produce an apparatus of this character with the parts made of wood, plastic or metal, as found most suitable or desirable, to make the parts adjustable and even separable in such fashion as to facilitate storing the apparatus as a whole and/or making it portable.

Other objects and advantages of the invention will appear in further detail as the specification proceeds.

In order to facilitate ready comprehension of the invention, and particularly its salient features, this invention is illustrated on the accompanying drawings forming part hereof, and in which:

Figure 1 is a perspective view of an apparatus embodying the present invention in a practical form and illustrating this apparatus in the process of being used to produce a perspective view;

Figure 2 is a side elevation of the same apparatus as seen from the far end thereof in Figure 1;

Figure 3 is a reduced perspective view showing

2

a curve frame and a perspective rule assembly associated therewith as being separated from the rest of the apparatus and used alone;

Figure 4 is a diagram illustrating a method of producing the curves determining the form of the curve frame used in the apparatus;

Figure 5 is a plan view of the curve frame and a stationary board as well as a slidable frame shiftable against the mentioned board;

Figure 6 is a fragmentary view of the slidable frame in enlarged perspective showing a multiple supporting socket for a sighting scale providing for different positions of the latter;

Figure 7 is an enlarged section of detail illustrating a pin-attaching means for the curve frame of Figure 5, together with a supporting foot for this frame;

Figure 8 is an enlarged side elevation of a peep hole member with its supporting post and base socket mounted upon the stationary frame supporting the curve frame, parts being shown partly in section to disclose the interior construction;

Figure 9 is a view of the upright or standing board upon which the elevation of the object to be drawn is normally mounted;

Figure 10 is a perspective view of a point-locator square adapted to cooperate with and be mounted upon the board of Figure 9 and be shiftable across the surface thereof during use;

Figure 11 is a fragmentary view showing the reverse side of the lower portion of the point-locator square of Figure 10 in slightly enlarged form to disclose detail of a retaining hook for holding the straight-edge or locating member of Figure 10 in close association with the mentioned board;

Figure 12 is an enlarged side elevation of the sighting scale of Figures 1 and 2 indicating the manner in which it is mounted in one of the various sockets of the base or multiple-socket member shown in Figure 6;

Figure 13 is another enlarged view of the same sighting scale as seen from the left in Figure 12;

Figure 14 is an enlarged sectional detail of a pin mounting for attaching the stationary frame or board which supports the peep hole member and the vertical post as shown in Figures 1 and 2, the pin being shown partly in section to indicate its position and manner of holding the parts to the board;

Figure 15 is an enlarged plan of the perspective rule assembly normally cooperating with the curve frame of Figures 1, 3, and 5;

Figure 16 is a side elevation of the same perspective rule as seen from the left in Figure 15;

Figure 17 is a fragmentary perspective view of the peep hole member of Figures 1, 2, and 8, illustrating a modification thereof.

It is well known in the various fields of art, and even in the practical art including drawing that perspective views are the most difficult to produce, and always require the highest skill, which is sometimes not attainable by certain people, and in any event, not too well executed by even those who are skilled. Moreover, when a perspective view is very detailed and perhaps must be quite accurate, the difficulty is greatly increased.

After duly considering this problem, I have found it quite feasible to produce an apparatus which facilitates the production of perspective views which are quite accurate from elevations and plan views of the object to be reproduced in perspective, as will now be set forth in detail.

Throughout the various views the same reference numerals indicate the same or like parts. The present perspective drawing apparatus, as shown in Figures 1 and 2, primarily includes a stationary board 18 provided with a pair of pin mountings 19, 19 through which a pair of pins 20, 20 extend down into the supporting board or table 21 upon which the entire apparatus is mounted, as best seen in Figure 14, the point 22 of the pin extending into the wood sufficiently to hold the board 18 stationary during operation. Upon one end of this board is fixed a base socket 23 by means of screws 24, 24 into the tapered hole 25 of which is fitted the lower tapered end 26 of an upwardly-extending tubular post 27. Slidably projecting upward from this post is a rod 28 normally fixed in position within the tubular post 27 by means of a screw 29, the rod terminating at the upper end thereof in a stud 30 projecting upwardly with a driving fit into the lower portion of a peep hole member 31. The tapered hole 25, tubular post 27, rod 28, and stud 30 are all concentric and their common axis is perpendicular to the surface of the supporting board or table 21 on which the stationary board 18 is placed. The mentioned peep hole member is rearwardly cylindrical at 32 with a large bore 33 which terminates, at its center line, as close as practicable to the center line or axis of the post 27 and rod 28. A small peep hole 34 is drilled along the center line of peep hole member 31. From the opposite side a smaller bore 35 is drilled in a short distance with the inner end forming a flaring continuation of the peep hole 34 at 36, the thickness of the material at the lip of the peep hole being as thin as practicable. The construction described places the peep hole 34 directly on the axis line of the tapered hole 25, the tubular post 27, the rod 28, and the stud 30 and this arrangement obviates the necessity of providing a means for rotational indexing of the parts mentioned in order to insure that the peep hole will be in the desired location. The peep hole member 31 is mounted at an angle inclined downwardly in the forward direction, the large deep bore 33 serving as an eye piece which well overshadows the peep hole 34 and avoids stray light from being reflected to the eye when using the apparatus. For this same purpose the peep hole member 31 is constructed of a dark, preferably dull black material, or all surfaces of the bore 33, the peep hole 34, the smaller bore 35, and its inner end 36 are coated or chemically treated to produce a dark finish, preferably dull black.

For the purpose of cooperating with the peep hole member just described, a substantially rec-

tangular slidable frame 37 having a straight-edge 38 adapted to engage slidably against the edge 39 of the previously-mentioned board 18 is provided on its remote corner with a multiple-socket member or block 40 rigidly fixed to the frame and provided with a group of tapering sockets 41, 42, 43, 44 with their axes set at different angles as particularly indicated in Figure 6, and with their centers in line as shown in Figure 5 and all center lines lying in a single plane perpendicular to the supporting board or table 21 upon which the slidable frame 37 is placed. Each socket is adapted individually to receive the lower tapered end 45 of the base 46 of a sighting scale 47 whose effective working edge 48 is aligned with the central axis 49 of the tapered end 45, while the scale is also provided with a series of subdivisions and numerical indicia, as generally indicated at 50, in Figures 1 and 13, for example, for a purpose which will be explained presently. The near edge of slidable frame 37, as shown in Figure 1, is beveled and provided with a scale 51 disposed at an angle of 90° with the edge 39 of board 18.

In order to cooperate with the peep hole member and the sighting scale 47 just described, an upright mounting board 52 is provided having at one corner thereof a supporting bridge 53 provided with a pair of spaced feet 54, 54 while at the opposite lower corner the board is provided with a single foot 55 which cooperates with feet 54, 54 to support the board in a position at right angles to the supporting board or table 21 and to allow free movement of the board upon the supporting board or table. The board 52 is constructed so that its upper edge 56 and its lower edge 57 are both parallel to the surface of the supporting board or table. Upon this board is mounted an instrument which may be termed a point-locating square, generally indicated at 58, consisting of an upper sliding head 59 having a rear retaining flange 60 best seen in Figure 2, while forwardly a depending straight-edge 61 is rigidly secured to the head 59 at right angles to the lower edge 62 and provided upon one side with a beveled working edge 63, lengthwise along the edge of which is marked a brightly colored indicator stripe for the purpose of readily identifying the working edge. This stripe, preferably red in color, tapers to a point at the lower end as generally indicated at 64. Upon the lower end of the straight-edge 61 is fixed a rearwardly-projecting retaining hook 65 extending upwardly behind the lower edge 57 of mounting board 52 and together with flange 60 on the upper sliding head 59 serving to retain the straight-edge 61 in working contact with the forward surface of the mounting board. In order to allow removal of the point-locating square 58 from the mounting board and also proper positioning thereof upon the same board, the latter at one end of its lower edge 57 is provided with a clearance recess 66, the lower hook 65 being readily passed through the recess after the flange 60 has been engaged on the top edge of the mounting board. When the square 58 is thereupon slid sidewise along the upper edge or top of the mounting board, the hook 65 will engage the lower edge 57 and retain the straight-edge in association with the board. When in position on the mounting board 52, the straight-edge 61 extends down as far as practicable without actually making contact with the supporting board or table 21 on which the mounting board 52 is set. The back edge 67 of the straight-edge 61 is beveled as shown in Figure 11 to allow the straight-edge to ride up over the

edge of the sheet of paper that will be attached to the mounting board when the apparatus is in use.

Upon the mounting board in one upper corner is located an aperture 68 by which to suspend the board from a hook or the like upon the wall when not in use. However, the board serves for mounting an elevation, generally indicated at 69, of an object to be reproduced in perspective upon a sheet 10 mounted on table 21. The elevation 69 is mounted so that one axis of the drawing lies parallel with the surface of the supporting board or table 21. Upon the table is also mounted a plan view of the same object, as indicated at 71, this plan view being made to the same scale as the elevation 69, with the longitudinal edge 72 (which is parallel to one axis of the drawing) disposed at a 60° angle with the edge 39 of board 18 in order to provide the proper predetermined relation with the special curve frame and perspective rule combination which will be described next.

Thus, upon the opposite end of board 18 from that carrying the post 27 and the peep hole member 31 is fixed a special curve frame, generally indicated at 73, by means of a pair of removable screws 74, 74 the heads of which are countersunk flush with the surface of the curve frame. This curve frame 73, which represents a long series of various forms and curves that may be used, consists of three curved sides 75, 76 and 77, at the corners of which are located supporting feet 78, 78, 78, through which manually-inserted pins 79, 79, 79 extend down into table 21 to retain the curve frame in fixed position and yet space the same upwardly from the table a sufficient distance to provide a clearance for the sliding frame 37 therebeneath, details of one of said feet with the securing pin being shown in enlarged form in Figure 7. It may be mentioned that this particular curve frame 73 is laid out on the assumption that the view to be produced will be a three-point perspective the lower vanishing point of which may be termed V^1 , the right vanishing point of which may be termed V^2 and the left vanishing point of which may be termed V^3 . The locations of these vanishing points upon the picture plane with reference to the point 80 representing the axis of vision may be found by methods familiar to those skilled in the art of perspective drawing. Required to be known is the angular position of the object in relation to the picture plane and the perpendicular distance from the picture plane to the station point from which the object is viewed. Obviously, these factors may be varied within their limits thus producing an infinite number of combinations upon which a wide variety of practical designs for the curve frame may be based. Vanishing point V^1 serves to form a center for an arc determining the curvature of the upper curved side 75, as indicated in Figure 4, while the curves 76 and 77 are derived from the vanishing points V^2 and V^3 , as will be immediately explained.

A perspective rule for the curve frame, generally indicated at 81, includes a follower member 82 adapted to ride upon the curves 75, 76 and 77 having a pair of follower pegs or studs 83, 83 normally following the exterior edge of the curve upon which the follower member 82 may be located, while projecting transversely across the curve involved toward the interior of the curve frame 73 is the integral lug 84 beneath which a block 85 is fixed by a pair of screws 86, 86. To the bottom of this spacing block is se-

cured a drawing blade 87, preferably transparent and flexible in the nature of plastic, the two edges of which, 88 and 89, taper toward each other sufficiently so that when the follower 82 is placed with the studs 83, 83 in contact with the top curve 75 of the curve frame 73 and lines are drawn along each of the edges 88 and 89 with a pen or pencil, and extended, they will converge at the lower vanishing point V^1 , as shown by broken lines in Figure 5. As best seen in Figure 1, this spacing block is of sufficient thickness to space the drawing blade down in actual contact with the sheet intended to receive the perspective view.

In order to plot the curve 76, as particularly noted in Figure 4, assuming that point 86 coincides with the axis of vision and that circle 90 defines the limit of the cone of vision about the axis, the layout of the perspective rule 81 including essentially the positions of the studs 83, 83 and the positions of the edges 88 and 89 of drawing blade 87 may be employed. For the upper curve 75, a sufficient thickness of material for the frame is allowed beyond the cone of vision represented by circle 90, and in similar manner allowing for a sufficient thickness of material for the frame at the curve generally indicated at 76 exteriorly of circle 90, the layout of the perspective rule is first located with the drawing blade 87 lying so that in use a line drawn with pen or pencil along edge 88 and passing through point 86 would, if extended, pass through vanishing point V^2 and the studs 83, 83 would lie in contact with the outside edge of the curve 76. Thereafter the perspective rule 81 is assumed to be shifted downward along the curve until the upper stud 83 occupies the position formerly occupied by the lower stud 83, the drawing blade 87 being located so that in use a line drawn with pen or pencil along edge 88 would, if extended, pass through vanishing point V^2 . With the perspective rule 81 in the position described it is apparent that a new position for the lower stud 83 has been established, and furthermore it will be noted that this method of locating a new position for the lower stud may be repeated as often as desired. In similar fashion, it is possible to locate a series of new positions for the upper stud 83 by shifting the layout of the perspective rule 81 upward along the curve 76 so that the lower stud 83 successively occupies the positions previously abandoned by the upper stud 83, while in each case the drawing blade 87 is located so that in use a line drawn with pen or pencil along edge 88 would, if extended, pass through the vanishing point V^2 . Having thus established a series of stud positions 83, 83, 83, etc., it is a simple matter to produce the smooth curve 76 tangent to each stud. In similar manner, the opposite curve 77 may be formed as based on the vanishing point V^3 , but as the operation is substantially the same as just described for curve 76, it will perhaps be superfluous to go into the details at this point. There is, however, one feature that should be noted: When the curve 77 is produced the perspective rule layout is reversed so that edge 89 of drawing blade 87 is on the top instead of on the bottom as in the case of curve 76. Although different edges of the drawing blade 87 are used the method of construction remains the same. A line drawn along edge 89 of the drawing blade and extended will pass through the vanishing point V^3 whenever the studs 83, 83 are in contact with the curve 77.

The design of the curve frame 73 combined

with the perspective rule 81 is particularly advantageous because it permits the operator to draw along the top edge of the drawing blade 87 regardless of whether the perspective rule 81 is set on the right or on the left curve of curve frame 73 and also because it permits the operator to draw along either edge of the drawing blade 87 when the perspective rule 81 is set on the top curve of the curve frame 73. In addition, the conditions mentioned remain unchanged even if the curve frame 73 is turned over, reversing it right for left, as is possible when it is used alone as shown in Figure 3.

While a three-sided convexly curved frame is described, I do not wish to be limited to such form of curve frame nor to the exact curvature of the two curves 76 and 77, nor the upper curve 75, but may use other methods and other distances for plotting the curves and may also make the two curves 76 and 77 symmetrical if I so desire. In particular, I wish to include the possibility of employing a convexly-curved frame (not shown) consisting of three curves, each of which would be formed as an arc having a vanishing point as its center. This curve frame would be provided with supporting feet and mounting pins similar to those described hereinbefore. To be used in conjunction with the curve frame, I would provide a perspective rule similar to the one described hereinbefore, except that the drawing blade, instead of being symmetrical around the longitudinal axis of the rule, would be offset to one side sufficiently to bring one edge of the blade in line with said axis, and except that the integral lug and the spacing block on the follower member of the rule would be offset sufficiently to accommodate the drawing blade in its offset position. In addition, while the curve frame has been illustrated as made from sheet material, it is equally within the scope of my invention that it may be stamped out, die cast, formed from rods or sections bent to shape and joined together, or fabricated in any other way mechanically equivalent to the construction described. Thus, the curve frame 73 represents a series of different curve frames that may be used, the particular one shown and described being merely a good example which serves the present purpose.

Proceeding now to the operation of the device to produce a perspective view from the elevation 69 and the plan view 71, it may be mentioned in passing that the slidable frame 37 preferably has the open area 91 to lighten the structure and facilitate shifting the frame by using a minimum of material for the latter. Assuming that the plan view 71 is mounted as already mentioned, with its longitudinal near edge 72 disposed at an angle of 60° with the far longitudinal edge 92 of frame 37 which is parallel to the edges 38 and 39 of the frame and of the board 18, respectively, and also assuming that the elevation 69 is mounted on the mounting board 52 in erect position with one axis of the drawing parallel to the surface of the supporting board or table 21, the only remaining requirement is to have sheet 70 in place upon which to draw the perspective view.

At the outset it may be stated that inasmuch as the proposed perspective view is to be based on three vanishing points according to the curves 75, 76 and 77 of the curve frame 73, it will naturally be a three-point perspective. In order to line up the views properly in preparation for transfer of the elevation and plan views to the perspective sheet 70, the slidable frame 37 is first shifted to the position shown in Figure 5. In this

position point 80, representing the axis of vision on the perspective drawing, lies at the edge of scale 51 adjacent to graduation "4." Also in Figure 5 it will be noted that a center line 93 drawn through the central axes of the socket holes 41 to 44 and also through the central axis of the socket hole 25 forms an angle of 90° with the edge 39 of board 18. The plan view 71 is placed so that the center line 93 passes through the part of the plan view desired to be shown at the center of the perspective drawing. The plan view is set back from edge 92 of sliding frame 37 sufficiently to permit the mounting board 52 and the point-locating square 58 to clear the sighting scale 47 during the operation. The elevation view 69 is placed on the mounting board 52 at such a height that when the point-locating square 58 is aligned with the point on the elevation view 69 which will be represented at the center of the perspective drawing and simultaneously aligned at its lower end upon the point on the plan view 71 which will be represented at the center of the perspective drawing, then the axis of vision 94 shown in Figure 2 will approximately intersect the mentioned point on the elevation view. It will be noted that the axis of vision is at right angles to the working edge 48 of the sighting scale 47. The operation may be started by singling out the apex 95 of the elevation view 69 mounted on board 52, and then the point-locating square 58 may be slid along the upper edge of the board 52 until beveled edge 63 of straight-edge 61 exactly coincides with the apex 95. Then the entire board 52 with the straight-edge 61 in place as described is shifted sufficiently to locate the lower end of the edge 63 directly upon the apex 96 of the plan view 71. The point 95 on the elevation 69 and the point 96 on the plan 71 both indicate the same point on the object, this point being represented by the present position of point 95 in space.

The operator now sights through the peep hole 34 of peep hole member 31 at point 95 on the elevation 69 and shifts the slidable frame 37 along edge 39 of stationary board 18 until working edge 48 of the sighting scale 47 aligns with point 95 on the elevation 69, the line of sight 97 passing by the scale 47 at point 98. While the slidable frame 37 is in this position, the operator mentally notes the scale reading at point 98 on the sighting scale 47, transfers this reading to the corresponding scale 51 on slidable frame 37 and places a pencil dot on the perspective drawing at this point as indicated at 99. In similar manner, any desired point defined on the elevation and plan views may be transferred to the perspective drawing. The curve frame 73 and the perspective rule 81 are used in combination to draw all lines which, if extended, would pass through the vanishing points. Either edge 88 or edge 89 of drawing blade 87 may be used to draw the lines which vanish at the lower vanishing point V¹, but the top edge, whether it be edge 88 or edge 89, is used to draw all lines which vanish at vanishing point V² or vanishing point V³. For example, assuming point 100 has been located on the perspective drawing and it is desired to draw line 100—101, the perspective rule 81 is placed on the curve 75 of curve frame 73 in such a way that studs 83, 83 make contact with the edge of the curve and edge 88 (or edge 89) of the drawing blade 87 aligns with the point 100. The line 100—101 may then be drawn along the edge of the drawing blade. Again, assuming point 100 is located and line 100—102 was de-

sired, the perspective rule 81 would be placed on curve 76 of curve frame 73 and the line 100—102 drawn along the top edge (in this case edge 88) of drawing blade 87. Finally, assuming point 100 was located and line 100—103 was desired, the perspective rule 81 would be placed on curve 77 and the line 100—103 drawn along the top edge (in this case edge 89) of drawing blade 87. The other perspective lines for completing the view are ascertained by means similar to those just described. The angular lines, such as line 99—104, are, of course, drawn without reference to the curve frame.

The method outlined is that which is followed for drawing any object in perspective so long as an elevation and a plan view thereof on the same scale are simultaneously used. Upon occasion it may facilitate the execution of the perspective view to have two elevations of the object, one a side elevation, and the other an end elevation, mounted upon opposite sides of the mounting board 52. If it is then desired to employ the view on the reverse side of the board, it is merely necessary to remove the point-locating square, reverse the board, and replace the square on the forward side. The only point which requires to be carefully observed in order to obtain an accurate result is that the two views be mounted at the same level.

It may upon occasion be desirable to use the curve frame 73 combined with the perspective rule 81 without employing the other parts of the apparatus, and hence, by removing screws 74, 74 this frame is released from board 18 and the pins 79, 79, 79 may be inserted in feet 78, 78, 78 to anchor the frame to the supporting board or table 21. The perspective rule 81 may then be used on the curve frame 73 to draw all lines which, if extended, would pass through the vanishing points. The operator must judge the length of these lines by eye, the perspective being then, of course, similar to that produced while using the entire apparatus already described, except for inaccuracies of judgment on the part of the operator. When the curve frame 73 is used alone this way it is possible to turn it over right for left inasmuch as the feet 78, 78, 78 extend upwardly above the frame as far as they do below it, and it may then be used to draw a 60° by 30° perspective instead of a 30° by 60° perspective.

The remainder of the apparatus, exclusive of the curve frame 73 and the perspective rule 81, may also be used alone to produce a perspective drawing. In this case the various points are plotted on the perspective view and connected together by lines with the aid of a straight-edge or drafting curve as required. When used in this way, it is obvious that the plan view 71 may be set at any angle of position and that the axis of vision 94 may be directed at any angle of slant within the adjustable range of the apparatus. This is possible because the removal of the curve frame 73 and the perspective rule 81 obviates the necessity of conforming to the conditions imposed thereby.

It is possible to draw an actual object with the apparatus by removing the mounting board 52 together with its point-locating square 58 and mounting the object within the cone of vision. The object, if small enough, may be set in position on the drawing table and blocked up to the correct height. If the object is too large to be set on the table, then the machine must

be placed so that the table will not obscure the extended cone of vision.

It will be observed that a two-point perspective may be produced by mounting the plan view at an angle with edge 92 of the slidable frame 37, inserting the sighting scale 47 in the tapered hole 44 of the multiple-socket block 40 (thus placing it in a vertical position) and adjusting the peep hole member 31 so that the axis of vision 94 lies horizontal. Of course, if a two-point perspective is to be produced, the curve frame 73 and perspective rule 81 can again be used when their design has been altered accordingly. If it is desired to draw a one-point perspective, the plan view 71 must be mounted with one of its axes parallel to edge 92 of slidable frame 37, while the adjustment of sighting scale 47 and peep hole member 31 remain the same as described for two-point perspective. Again the curve frame 73 and perspective rule 81 can also be used when their designs have been varied to suit this purpose.

While I have shown and described the post 27 and the upper supporting rod 28 of peep hole member 31 as forming an extensible unit so as to raise the peep hole member 31 by loosening set screw 29, it is evident that this post could be rigid and non-extensible if so desired. Furthermore, the base 23, instead of being affixed to the board 18 by means of screws 24, 24, could also be integral with the stationary board 18 if the latter is made of plastic, die cast metal, or similar material, and I reserve the rights to such forms of the invention. It is likewise within the purview of my invention to have the upper portion of the post 28, whether the post be rigid or extensible as described, formed with a yoke 105 with pivots 106, 106 (one shown) for supporting an adjustable peep hole member 107, the pivots being naturally aligned through the peep hole within peep hole member 107 in order that the peep hole will not be disturbed in position upon adjusting member 107 so that it will line up with the desired axis of vision. The post 108 supporting the yoke 105 may either be riveted or brazed thereto or made integral with the yoke 105.

Returning now to the apparatus shown in Figures 1 and 2, the removal of anchor pins 20, 20 from members 19, 19 on board 18 and pins 79, 79, 79 from feet 78, 78, 78 on curve frame 73 frees the stationary board 18 and the curve frame 73 from the supporting board or table 21, while removal of post 27 from base 23 allows the stationary board 18 with its attached curve frame 73 to be stored away in flat condition or hung upon a peg on the wall. In similar fashion, the removal of scale 47 from multiple-socket member 40 will allow frame 37 to be stored away or hung upon the wall together with the board 18 and frame 73, while mounting board 52 may be either stored away in flat condition or hung up by its suspension aperture 68 after duly removing the point-locating square 58 therefrom by shifting it so as to cause the rear hook 65 to be released through recess 66 after which the upper sliding head 59 of the square 58 may simply be lifted off the board 52 and the square 58, with post 27, rod 28, and peep hole member 31, and also scale 47, and likewise rule 81, and pins 20, 20, and 79, 79, stored in a box or receptacle intended for this purpose.

While I have already suggested certain modifications which are possible, it is manifest that further modifications may also be resorted to and

parts and features may thus be modified or used without others within the scope of the appended claims.

Having now fully described my invention, I claim:

1. A perspective drawing apparatus including movable supporting means for supporting an elevation of the object to be drawn in one position, stationary means for supporting a plan view of the same object in another position, stationary adjustable sighting means for viewing the elevation, means for locating each given point upon said elevation directly over the corresponding points upon the plan view in succession, a shiftable member having a sighting scale projecting transversely to the line of sight from the stationary sighting means, and a second scale fixed upon the shiftable member adjacent to the site of the proposed perspective view to be drawn, the sighting scale and the second scale having mutually corresponding indicia.

2. A perspective drawing apparatus including movable supporting means for supporting an elevation of the object to be drawn in one position, stationary means for supporting a plan view of the same object in another position, stationary adjustable sighting means for viewing the elevation, means for locating each given point upon said elevation directly over the corresponding points upon the plan view in succession, a shiftable member having a sighting scale projecting transversely to the line of sight from the stationary sighting means, a second scale fixed upon the shiftable member adjacent to the site of the proposed perspective view to be drawn, the sighting scale and the second scale having mutually corresponding indicia, and guide means for drawing lines from and/or between the points ascertained adjacent to said second scale corresponding to the points of said elevation sighted upon the sighting scale in various shifted positions of said shiftable member, said guide means including an open frame which is stationary with reference to the stationary sighting means and consists of three curve members joined at the ends thereof to form the frame enclosing the imaginary circle defining the field of sight for drawing the proposed perspective view, and a perspective rule having converging side edges and at one end having a follower member adapted to slide upon the curve members of the frame with a pair of follower pins adapted to engage against the edge of the curve member upon which the follower member is located.

3. A perspective drawing machine including a vertically-disposed movable supporting member for supporting an elevation of the object to be drawn, stationary adjustable sighting means for viewing the elevation, means for locating each given point upon said elevation in predetermined relation to the corresponding points in succession upon a stationary plan view of said object when occupying a position beneath said vertically-disposed supporting member and the elevation mounted thereon, a shiftable member having a forwardly-inclined sighting scale projecting transversely to the line of sight extending from the stationary sighting means to said elevation, and a second scale fixed upon the shiftable member adjacent to the site of the proposed perspective view to be drawn, the sighting scale and the second scale having mutually-corresponding indicia.

4. A perspective drawing apparatus including a shiftable upright support for supporting an ele-

vation of the object to be drawn in perspective, adjustable means upon the upright support for individually locating each given point upon the elevation directly over the corresponding points upon a stationary plan view of the same object in succession, a stationary lateral guide member having an elevated adjustable viewing member mounted thereon for viewing said elevation, a shiftable member having one edge thereof adapted to slide against the stationary lateral guide member and having a projecting sighting scale extending upwardly between said elevation and the viewing member transversely to the line of sight from the latter, a second scale disposed fixedly on the shiftable member at substantially a right angle to the mentioned one edge thereof for determining points upon the proposed perspective view corresponding to the given points viewed at the edge of the sighting scale upon the elevation in shifted positions of said shiftable member, mutually-corresponding indicia upon the sighting scale and the second scale to identify on the latter the points indicated on said sighting scale, a curve frame having an interior open area fixedly associated with the stationary lateral guide member including a plurality of curved elongated members connected together at the ends thereof to form the curve frame and enclose the imaginary circle defining the perspective drawing field in said open area, and a follower member adapted to rest upon the curve frame having a pair of follower means engaging against the edge of the individual curved member involved, and a perspective rule having two drawing edges inclined with respect to the center longitudinal axis of the rule, said rule being directed inward from the follower member upon said open area of said curve frame for drawing lines from and/or between the points in said open area within the latter curve frame ascertained by the indicia upon said second scale.

5. A perspective drawing apparatus including an upright shiftable mounting board to be arranged upon a table or the like for supporting an elevation mounted thereon of the object to be drawn in perspective, a pendent straight-edge having a supporting head slidably mounted upon the upper edge of the mounting board, the pendent straight-edge having a working edge for indicating given points upon the elevation upon said mounting board, the latter being shiftable to direct the lower end of the working edge of the pendent straight-edge directly upon the corresponding points in succession upon a stationary plan view of the same object supported by the table, a stationary supporting board mounted upon the table and having a lateral guiding edge and a post mounted upon one end thereof carrying an adjustable viewing member, a curve frame member secured upon the other end of the supporting board and having an interior open area defining a working space for drawing the proposed perspective view, supporting feet for spacing the curve frame upward from the table supporting it, removable means for retaining the supporting board and curve frame member stationary on said table, a slideable frame guided in movement upon said table against the lateral guiding edge on said supporting board, an upwardly-directed inclined viewing scale projecting from one portion of the slideable frame transversely to the line of sight extending from the viewing member to said elevation, a second scale fixed upon another portion of the slideable frame adjacent to the curve frame and disposed at a right angle to said lateral guid-

ing edge on said supporting board, mutually-corresponding indicia upon the inclined viewing scale and the second scale for identifying the points in the working space within said curve frame member corresponding to the given points viewed along said inclined viewing scale upon said elevation in various shifted positions of said slidable frame, and a perspective rule in said working space having two drawing edges inclined with respect to the central longitudinal axis of said rule for drawing lines from and/or between the points ascertained in said working space adjacent to said second scale, and a follower portion secured to said perspective rule for engaging upon the curved portions of said frame member.

6. A perspective drawing apparatus including an upright shiftable mounting board for supporting an elevation mounted thereon of the object to be drawn in perspective, supporting feet at the lower corners of the mounting board for spacing the lower edge thereof from the table supporting it, the mounting board having both upper and lower edges parallel to the supporting table, a pendent straight-edge having a supporting head slidably mounted upon the upper edge of the mounting board, the pendent straight-edge having a beveled working edge for alignment with given points upon the elevation mounted on said mounting board, the latter being shiftable to direct the lower end of the working edge of the pendent straight-edge directly upon corresponding points in succession on a stationary plan view of the same object, the plan view being mounted upon the supporting table, a retaining flange upon the supporting head and a retaining hook near the lower end of said pendent straight-edge for engaging with the upper and lower edges of said mounting board respectively to hold the straight-edge against the latter along its entire length, the lower edge of said mounting board having a clearance recess at one end for releasing the retaining hook of said straight-edge and thereby releasing the latter from the board, a stationary supporting board having a lateral guiding edge and a post detachably mounted upon one end thereof carrying an adjustable viewing member with the line of sight thereof inclined downward toward an intermediate portion of the elevation on the mounting board, a curve frame member including three elongated convexly-curved members secured together at the ends thereof to form a three-sided frame secured upon the other end of the supporting board and having an intermediate open area defining a working space for drawing the proposed perspective view, supporting feet for spacing the curve frame upward from the table supporting it, removable means including anchoring pins for retaining the supporting board and curve frame stationary on said table, a slidable rectangular frame guided in movement upon said table against the lateral guiding edge on said supporting board, an upwardly-directed inclined and detachably mounted viewing scale projecting from one end of the slidable frame transversely to the line of sight from the viewing member toward said elevation, a second scale fixed upon the other end of the slidable frame adjacent to the curve frame and disposed at a right angle to said lateral guiding edge on said supporting board, mutually-corresponding indicia upon the inclined viewing scale and the second scale for identifying the points in the working space within said curve frame corresponding to the given points viewed along said inclined viewing scale upon said elevation in various shifted

positions of said shiftable frame, and a perspective rule in said working space having two drawing edges inclined with respect to the central longitudinal axis of said rule for drawing lines from and/or between the points ascertained in said working space adjacent to said second scale, and a follower portion secured to said perspective rule at one end thereof for engaging upon the curved portions of said frame member in order to guide said rule into proper drawing positions.

7. A perspective drawing machine including a shiftable upright support for supporting an elevation of the object to be drawn in perspective, a pendent locating straight-edge shiftable upon the upright support for individually locating each given point upon the elevation directly over the corresponding points in succession upon a stationary plan view of the same object, a stationary lateral guide member having an adjustable elevated viewing member fixed thereon for viewing said elevation, a shiftable member having one edge thereof adapted to slide against the stationary lateral guide member and having a member fixed thereon with a tapered socket, a sighting scale having a tapered lower end fitting said tapered socket and projecting upwardly between the viewing member and said elevation transversely to said line of sight, a working edge on the sighting scale coinciding with the central longitudinal axis of the tapered lower end thereof and of the socket occupied thereby, a second scale rigidly disposed on the shiftable member at substantially a right angle to the mentioned one edge thereof for determining points upon the proposed perspective view corresponding to the given points viewed at the edge of the sighting scale upon the elevation in shifted positions of the shiftable member, and mutually-corresponding indicia upon the sighting scale and the second scale to identify on the latter the points indicated on said sighting scale.

8. A perspective drawing machine including a shiftable support for supporting an elevation in upright position of an object to be drawn in perspective, a locating straight-edge adjustably mounted on the shiftable support for individually locating each given point on the elevation directly above the corresponding points in succession on a stationary plan view of the same object, a stationary lateral guide member having upon one portion thereof a base with a socket formed therein, an upwardly hollow post having the lower end fitting detachably in the socket, an upper post member extending adjustably down into the hollow post, means upon the latter for fixing the upper post member at various elevations in said hollow post, a yoke rigid upon the upper end of the upper post member, a hollow peep hole member having a central peep hole portion mounted in said yoke on a horizontal axis passing through said peep hole portion, and the mentioned socket, upwardly hollow post and upper post member being concentric and their common vertical axis also passing through the mentioned peep hole portion, a shiftable frame having one edge sliding against the stationary lateral guide member and having a forwardly-inclined sighting scale projecting upwardly from one portion thereof between the peep hole member and the elevation on the shiftable support transversely to the line of sight extending therebetween, a second scale rigidly disposed upon another portion of said shiftable frame at a right angle to the mentioned one edge thereof for determining points

upon the proposed perspective view corresponding to the given points viewed at the edge of the sighting scale upon said elevation in various shifted positions of said shiftable frame, and mutually-corresponding indicia upon the sighting scale and the second scale to identify on the latter the points indicated on said sighting scale.

9. A perspective drawing machine including an upright shiftable mounting board arranged upon a supporting table or the like for supporting an elevation of the object to be drawn in perspective, a pendent straight-edge having a supporting head slidably mounted upon the upper edge of the mounting board, means for holding the straight-edge against the latter in various shifted positions thereof along said mounting board, the straight-edge having a beveled working edge for indicating given points upon the elevation mounted on said mounting board, the latter being shiftable to direct the lower end of said beveled working edge of the pendent straight-edge directly upon the corresponding points in succession upon a stationary plan view of the same object when disposed horizontally on the supporting table adjacent to the lower end of said straight-edge, a detachable stationary board having a lateral guiding edge and a base member having a tapered socket fixed upon one end of the board, an upright post having a tapering lower end detachably fitting into the tapered socket in the base member and upon the upper end having a peep hole viewing member, the central axis or line of sight thereof inclined downward toward an intermediate portion upon said elevation on said mounting board in a vertical plane disposed at a right angle with the guiding edge of the stationary board, the peep hole portion being disposed on the longitudinal axis of the post and the tapered socket in said base, a plurality of elongated curved members secured together at the ends thereof to form a curve frame which is secured to the other end of said stationary board and has a plurality of supporting feet to hold the frame spaced from the table supporting it, the curve frame having an intermediate open area

45

enclosing an imaginary circle forming a working field for drawing the perspective view, a movable frame slidable upon the table supporting it against the guiding edge on said stationary board and upon one end having a tapered socket member fixed thereon, a sighting scale having the lower end tapered to fit said tapered socket member and a working edge in line with the central axis of the tapered lower end and socket member and located in a vertical plane at a right angle with said guiding edge of said stationary board, a second scale formed upon the other end of the movable frame and disposed substantially parallel to the vertical plane coinciding with the line of sight or central axis of said peep hole member, the movable frame at the end carrying the second scale being slidable beneath the curve frame, mutually-corresponding indicia on the sighting scale and the second scale for identifying the points in the proposed perspective view in said working field corresponding to the given points viewed along the working edge of said sighting scale upon said elevation in various shifted positions of said movable frame, and a rule movable in said working space for drawing lines from and/or between the points ascertained therein adjacent to said second scale, and guide means fixed on one end of the latter rule engaging with the curved members on said curve frame for guiding said rule into proper perspective positions for drawing said lines.
